(57) **CLAIM**

The ornamental design for a fruit snack, as shown and described.

DESCRIPTION

FIG. 1 is front, top and right side perspective view of a fruit snack according to our design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevation view thereof; and,

FIG. 7 is a left side elevation view thereof.

The evenly-spaced broken lines in FIGS. 1-3, 6 and 7 illustrate portions of the fruit snack that form no part of the claimed design. The dash-dot-dash broken lines in FIGS. 1-3, 6 and 7 illustrate the boundary of the claimed design which forms no part thereof.

1 Claim, 4 Drawing Sheets
